UNITED STATES PATENT OFFICE.

GEOEGE F. VOIGHT, OF OAKLAND, CALIFORNIA.

WIRE FASTENER.

Application filed December 19, 1925. Serial No. 76,561.

My invention relates to improvements in wire fasteners particularly adapted for securing wire lath in outstanding relation to the wall sheathing of stucco structures, although also useful for other purposes; and one of the objects of the invention is to provide a wire fastener in which a spacing element is carried on a driven element and operatively relatively movable for cooperating therewith for engaging and binding the wire lath between portions thereof for spacing and attaching it to the wall sheathing; a further object is to provide means projecting out from the side of the driven element, engageable with the spacing element for normally limiting its movement on said driven element longitudinally of the latter.

With the foregoing and still further objects and purposes in view which will appear as the description proceeds, my invention resides in the combination and arrangement of parts and in the details of construction hereinafter described and claimed, it being understood that changes in the precise embodiment of the invention herein disclosed can be made within the scope of what is claimed, without departing from the spirit of the invention.

In the accompanying drawings—

Figure 1 is a side elevation of a wire fastener constructed in accordance with my invention, disposed in engagement with a fragmental portion of the wall sheathing preparatory to attaching it thereto, and a cross sectional view of a portion of the wire lath supported by the spacing element;

Figure 2 is a sectional elevation of the wall sheathing with the fastener shown in vertical elevation attached thereto, a portion of the wire lath confined between the head of the driven element and the spacing element, and a section of stucco composition in the immediate background;

Figure 3 is another view in elevation of the fastener as it appears in its permanent position attached to the wall sheathing;

Figure 4 is a vertical median sectional view of the lower portion of the fastener, showing the spacing element in its normal position relative to the driven element, and a transverse sectional view of a portion of the wire lath seated on the spacing element;

Figure 5 is a plan view on line 5'—5' of Fig. 1;

Figure 6 is an intermediate plan view on line 6'—6' of Fig. 3;

Figure 7 is a sectional view on line 5'—5' of Fig. 1, of the nail removed from the spacing element;

Figure 8 is a sectional view of the nail on line 8'—8', Fig. 1; and

Figure 9 is a strip of sheet metal from which the spacing element is formed, showing a step in its construction.

Figures 4, 5, 6, 7 and 8 being drawn on a larger scale than Figures 1, 2, 3 and 9.

Referring to the drawings in detail, throughout which like reference characters designate like parts:

The numeral 1 designates the wall sheathing of a stucco structure, and comprises, preferably, boards of equal thickness attached in close-jointed order at the face of the studs and other timbers forming the frame work of the exterior walls thereof.

Across the face of the wall sheathing 1 is preferably disposed a sheathing of building paper 2, which is intended as a waterproofing for preventing exterior moisture that may find its way through the stucco composition, penetrating to the wood-work of the structure. However, if preferred, the building paper may be eliminated.

Inasmuch as it is entirely optional whether or not the wall sheathing 1 is provided with the building paper 2, and as the employment, or omission, thereof does not in any way affect the application or operation or functioning of the present fastener, the term, "wall sheathing", or "sheathing", when the same appears hereinafter, is intended to be construed to mean any wall covering attached to the frame timbers of the wall, either with or without another covering of building paper, to which the fasteners are attached and which forms the backing against which the stucco composition is spread.

3 designates the spacing element, and 4 the driven element, of my improved wire fastener.

The driven element 4 comprises a nail having the conventional cylindrical shank 5 and a flat head 6.

Intermediate the ends of the shank 5 are a pair of side projections 7, which project laterally outwardly from the periphery of the shank on opposite sides and are formed, preferably, by pressing indentations 8 into the shank thereby forcing portions thereof outwardly a proper distance and in the form desired.

The spacing element 3 comprises a strip of sheet metal bent to form, an intermediate lath seat 9, which is provided with a central opening 10 and has its ends folded double to form a pair of opposed upwardly projecting retaining lips 11 inclining outwardly towards their upper ends, and side supports 12 extending from the base of said lips downwardly equal distances and terminate at right angles inwardly equal distances in a common plane to form a base plate 14.

The free ends of the side supports 12 are provided with opposed arcuations 13, which cooperate to form a central opening 15 extending through the base plate 14.

The spacing element is in the general form of a box open at the front and rear when viewed in elevation as shown in Figs. 20 1, 2 and 4.

The spacing element 3 is normally supported on the shank 5 in the relative position as best shown in Figs. 1 and 4, and in which position the projections 7 are disposed between the lath seat 9 and the base plate 14, with the shank 5 projecting through the openings 10 and 15. While the diameters of the openings 10 and 15 are preferably such, relative to the diameter of the shank 5, that the spacing element may freely rotate on the shank, they are substantially smaller in diameter than the maximum diameter of said shank through the projections 7, which causes the latter to engage the lower side of the lath seat 9 when it is moved vertically downwardly, thereby normally limiting its movement in the latter direction, and to engage the upper side of the base plate 14 when the spacing element is moved vertically upwardly, thereby normally limiting its movement in an upwardly direction, relative to the driven element.

The spacing element is preferably "factory assembled" on the driven element, and the projections 7 are preferably formed after assembling.

To apply the fastener for attaching the wire lath 16 to the wall sheathing 1, its forward end including the spacing element 3, is projected through the desired mesh of the lath, with the shank 5 disposed in close relation with one of the wires forming said mesh and with the point of the shank engaging the wall sheathing (see Fig. 1.), it is then driven into the latter until the head 6 engages and binds the wire lath firmly against the lath seat 9 between one of the lips 11 and the shank 5, and the base plate 14 firmly seats against the sheathing (see Fig. 2).

As the shank 5 is driven forwardly into the wall sheathing, and the spacing element engages the latter, the projections 7 engage and force their way through the base

plate 14, either by tearing out small portions of the plate at the margin of the opening 15, by forcing the two members forming said plate apart sufficiently to admit of the projections passing therebetween, or by both tearing and forcing said members apart. Such tearing or forcing apart of these members does not in the least interfere with the proper functioning of fastener for attaching and spacing the lath wire to the wall sheathing.

The fasteners may be disposed along the wall sheathing at such intervals as found best suited for the work to be performed. I have found by practice that spacing them about 8 inches apart provides ample fastening for the general type of wire lath. It is to be understood that any suitable variety or type of lath may be attached with my fasteners, including the type commonly known as "poultry wire".

After attaching the wire lath to the wall sheathing, the stucco composition is preferably applied by spreading it on the wall sheathing and on and around the wire lath and the exposed portions of the fasteners, until a coating of suitable thickness is obtained.

The retaining lips 11 are adapted for limiting lateral movement of the lath 16 on the lath seat 9, and also for engaging the lath for stretching it preparatory to securing it to the wall sheathing.

Heretofore wire fasteners have been invented in which the spacing element is frictionally held on the driven element by pressing thereagainst from opposite sides. This arrangement however I have found does not work out very well in practice. In the first place, for economical reasons it is necessary to construct the spacing element of comparatively thin metal, which does not provide sufficient spring pressure against the comparatively smooth surface of a nail to resist removal therefrom during the handling, packing and transporting of the fasteners, and in the second place, when the fastener is employed, as is frequently desirable, for stretching the lath preparatory to attaching it to the sheathing, and for doing which the spacing element is made to engage the lath to be stretched and the fastener then used as a lever for drawing the lath so engaged in the direction in which it is desired to stretch it, it has been found that the resistance of the lath invariably draws the spacing element down to the extreme lower end of the driven element, and not infrequently strips it off entirely, without accomplishing the desired stretching of the lath. The spacing element of my improved fastener is, for reasons of the projections 7, more securely retained on the driven element, and may be readily employed for stretching the lath

without danger of moving the spacing element from its normal position on the driven element.

I claim:

- 5 1. A wire fastener comprising, a nail having a shank provided on one side with a lateral projection, and a spacing element having portions engaging portions of said shank above and below said projection.
- 10 2. A wire fastener comprising, a nail having a shank provided with a lateral projection on one side, and a spacing element embracing portions of said shank above and below said projection, and engageable with the latter when moved along said shank longitudinally in either direction.
- 15 3. A wire fastener comprising, a spacing element having a pair of spaced openings, and a driven element having a shank projecting through said openings, said shank having a projection on one side disposed between said openings, said spacing element engageable with said projection when moved in either direction along said shank longitudinally, for normally limiting its movement in said directions.
- 20 4. A wire fastener comprising, a spacing element formed of a strip of flat metal and provided with a lath seat, and a cooperating nail having a shank projecting through the spacing element through said lath seat, said shank having a lateral projection on one side adapted to engage said lath seat for normally limiting the movement of said spacing element on said shank in one direction axially relative thereto.
- 25 5. A wire fastener comprising, a spacing element having a portion adapted to seat against a support, and a cooperating nail having a shank projecting through said portion, said shank having a lateral projection on one side engageable with said portion for normally limiting the movement of said por-

tion in a direction towards the head of said nail.

6. A wire fastener comprising, a driven element having a shank provided with a lateral projection on one side, and a cooperating spacing element having portions disposed on opposite sides of said shank above said projection and having portions disposed on opposite sides of said shank below said projection, said projection engageable with spaced portions of said spacing element for normally limiting its movement vertically on said shank in either direction.

7. A wire fastener comprising, a spacing element having a portion adapted to seat against a support, said portion having an opening, and a cooperating nail having a shank projecting through said opening, said shank having a lateral projection on one side engageable with the upper side of said portion for normally limiting the upward movement of said spacing element relative to said shank, said projection adapted to penetrate said portion at the margin of said opening and pass through said portion when said shank is operatively driven in said support for attaching said spacing element thereto.

8. A wire fastener comprising, a spacing element formed of a strip of sheet metal and embodying a lath seat having lath retaining projections on each end and an opening between said projections and means below said lath seat engageable with a support for supporting said lath seat in spaced relation therewith, and a cooperating nail projecting through said opening, said nail having a head, said nail adapted to be projected in said support for causing said head to engage and bind a lath wire on said lath seat between one of said projections and said nail.

GEORGE F. VOIGHT.
